UNITED STATES PATENT OFFICE

2,449,465

FLOOR MAT

Jacob E. Flaker, Barberton, Ohio

Application September 23, 1946, Serial No. 698,636

4 Claims. (Cl. 15—215)

1

This invention relates to floor mats.

One object of the invention is to provide a floor mat having improved flexible foot-wiping means thereon for effective and efficient removal of dirt from the bottoms of shoes, improved means also being provided for retrieving the dirt thus removed to obviate depositing the same on the supporting surface under the mat, and therefore eliminating the usual necessity for sweeping said floor surface to remove the collected dirt.

These and other objects of the invention will be manifest in the following brief description and the accompanying drawings.

Of the accompanying drawings:

Figure 1 is a top plan view, partly broken away and partly in phantom, of a floor mat embodying the features of the invention.

Figure 2 is a top plan view, greatly enlarged, illustrating a fragmentary portion of the mat of Figure 1.

Figure 3 is a fragmentary cross-section, taken substantially on the line 3—3 of Figure 2.

Figure 4 is a fragmentary vertical cross-section through vulcanizing apparatus for producing the floor mat of Figures 1, 2 and 3.

Referring particularly to Figures 1, 2 and 3 of the drawings, the numeral 10 designates a floor mat comprising a relatively thin pad of flexible, resilient material, such as vulcanized rubber or synthetic elastomer. Provided in the normally upwardly presented broad lateral surface of the pad 10 may be a honey-comb of relatively small recesses 11 having annular walls tapering inwardly to substantial depth, but to less than the thickness of the pad, as best shown in Figure 3. As best shown in Figures 1 and 2, the general pattern and spacing of the recesses 11 is such that groups of three immediately adjacent recesses of the pattern each define a distinct substantially solid portion bounded as shown by arcuate wall surfaces of said three adjacent recesses and being of approximately the same thickness of the mat, a plurality of such resultantly closely spaced solid portions being adapted to support the weight of a person standing on the mat without substantial give or flexing. The wall portions between any two immediately adjacent recesses, however, are relatively thin and flexible, that is intermediate said solid portions, to be capable of substantial flexing action upon wiping of the feet on the mat. To assist the wiping action referred to, or in other words to compensate for the relative stiffness of said dividing

2

wall portions, annular, tangentially interconnecting, flexible ribs 12 may be provided around the mouths of the recesses 11.

In the use of the mat, as for example as a door mat, a user wipes his feet across the top surface thereof, and as the average foot is large enough to overlie a substantial number of the recesses 11, the ribs 12 very effectively remove dirt from the bottoms of the shoes. Because the recesses 11 do not extend through the mat, the removed dirt will be retained within the recesses, so that periodically the mat may be shaken to deposit the dirt therefrom in an appropriately convenient place. As no dirt will be collected on the floor surface beneath the mat, the usual aggravating operation of sweeping under the mat is eliminated. The inwardly tapered sides of the recesses facilitates ready removal of dirt therefrom which may 20 become caked.

In Figure 4 is illustrated the vulcanizing apparatus for producing the above described floor mat. A mold unit 13, comprising upper, lower and intermediate sections 14, 15 and 16, respectively, is removably received between upper and lower relatively movable platens 17 and 18 of a suitable vulcanizing press. The mold unit 13 is shown in closed position, in which it is engaged under heavy pressure between the upper and lower mold members, and the arrangement may be such that the mold unit is removable from the press upon separating the movable press platens for loading and unloading the mold.

35 The intermediate mold member 15 may have on the upper and lower faces thereof, relatively shallow mat-forming cavities 19 and 20, the depths of which correspond to the thickness of the mats. For forming the dirt receiving recesses 11, 11 of the mats, oppositely disposed tapered buttons or discs 21, 21 are secured to the oppositely disposed inner faces of the cavities 19 and 20, in closely spaced relation according to the desired spacing of the honey-comb of recesses, as previously described. For securing the buttons 21 to the intermediate mold section, pins 23, 23 are received through aligned apertures in the buttons and in the web portion 24 defined between the cavities 19 and 20. The outer ends of the recesses in the buttons are shown countersunk for receiving correspondingly shaped retaining heads on the opposite ends of the pins, one of which may be a stock head with the other being formed as by riveting on assembly. Annular relatively narrow, recesses 25 are

provided on the inner faces of the cavities 19 and 20 around each of the buttons 21 for forming the ribs 12 of the mat.

Thus the vulcanizing apparatus described above is capable of use for vulcanizing a mat 10 on each side of the intermediate mold member 16, the mats being formed in the press in known manner under requisite pressure and vulcanizing heat.

It will be seen that by the provision of separate buttons 21 for forming the ribs 12 of the mat, a substantial amount of expensive machining or engraving in the article-forming cavities of the mold is obviated. Also, any number of the buttons 21 are easily replaceable upon becoming worn or broken, without necessarily affecting the others. The necessity for replacement of the complete intermediate mold section thereby may be eliminated.

Modifications of the invention may be resorted to without departing from the spirit thereof or the scope of the appended claims.

What is claimed is:

1. A floor mat, comprising a relatively thin one-piece pad composed of resilient material, said pad having a honeycomb of recesses extending inwardly of one broad lateral face thereof, said recesses having generally arcuate inner wall surfaces, said recesses being closely spaced and arranged to have a general pattern in which groups of at least three immediately adjacent recesses of the pattern define a distinct substantially solid portion bounded by a corresponding number of arcuate wall surface portions of the adjacent recesses and being of approximately the thickness of the pad and a plurality of which will support the weight of a person standing on the pad without substantial flexing of said solid portions, the portions of said pad between any two of the immediately adjacent recesses being relatively thin and flexible as compared with said solid portions and thereby adapted to flex upon wiping of feet on the pad.

2. A floor mat, comprising a relatively thin one-piece pad composed of resilient material, said pad having a honeycomb of recesses extending inwardly of one broad lateral face thereof, said recesses having generally arcuate inner wall surfaces, said recesses being closely spaced and arranged to have a general pattern in which groups of at least three immediately adjacent recesses of the pattern define a distinct substantially solid portion bounded by a corresponding number of arcuate wall surface portions of the adjacent recesses and being of approximately the thickness of the pad and a plurality of which will support the weight of a person standing on the pad without substantial flexing of said solid portions, the portions of said pad between any two of the immediately adjacent recesses being relatively thin and flexible as compared with said solid portions and thereby adapted to flex upon wiping of feet on the pad, said pad having on said face thereof integral well-defined ribs extending substantially continuously around each said recess and above the plane of said face adapted to provide for additional foot-wiping action thereon.

3. A floor mat, comprising a relatively thin one-piece pad composed of resilient material, said

pad having a honeycomb of recesses extending inwardly of one broad lateral face thereof defined by annular walls, said recesses being closely spaced and arranged to have a general pattern in which groups of at least three immediately adjacent recesses of the pattern define a substantially solid portion bounded by a corresponding number of arcuate wall surface portions of the adjacent recesses and being of approximately the thickness of the pad and a plurality of which will support the weight of a person standing on the pad without substantial flexing of said solid portions, the portions of said pad between any two of the immediately adjacent recesses being relatively thin and flexible as compared with said solid portions and thereby adapted to flex upon wiping of feet on the pad, said pad having on said face thereof integral well-defined annular ribs extending substantially continuously around each said recess and above the plane of said face adapted to provide for additional foot-wiping action thereon.

4. A floor mat, comprising a relatively thin one-piece pad composed of resilient material, said pad having a honeycomb of recesses extending inwardly of one broad lateral face thereof defined by annular walls, said recesses being closely spaced and arranged to have a general pattern in which groups of three immediately adjacent recesses of the pattern define a substantially solid portion bounded by three arcuate wall surface portions of the adjacent recesses and being of approximately the thickness of the pad and a plurality of which will support the weight of a person standing on the pad without substantial flexing of said solid portions, the portions of said pad between any two of the immediately adjacent recesses being relatively thin and flexible as compared with said solid portions and thereby adapted to flex upon wiping of feet on the pad, said recesses being inwardly tapered and extending inwardly of said face to a depth of less than the full thickness of the pad, said pad having on said face thereof integral well-defined annular ribs extending substantially continuously around each said recess and above the plane of said face adapted to provide for additional foot-wiping action thereon.
